UNITED STATES PATENT OFFICE.

ALEXANDER C. MARTIN, OF CHICAGO, ILLINOIS.

CAR-COUPING.

SPECIFICATION forming part of Letters Patent No. 436,796, dated September 23, 1890.

Application filed July 14, 1890. Serial No. 358,631. (No model.)

To all whom it may concern:

Be it known that I, ALEXANDER C. MARTIN, of Chicago, in the county of Cook and State of Illinois, have invented certain new and useful 5 Improvements in Car-Couplers, of which the following is a full, clear, and exact description, reference being had to the accompanying drawings, forming a part of this specification, in which—

10 Figure 1 is a central vertical longitudinal sectional view of my improved car-coupler. Fig. 2 is a plan view of the same, and Fig. 3 is a front end view showing the arm upon which the hook is formed as partly broken off 15 and in a raised position.

Corresponding letters of reference in the different figures indicate like parts.

The object of my invention is to provide a simple and efficient car-coupler, which may be 20 actuated by hand without danger to the operator, and which may be simple and durable in its construction and operation, all of which is hereinafter more particularly described and claimed.

25 Referring to the drawings, *a a* represent the ends of two freight-cars, while *b b* indicate the draw-heads, which are attached to the car in the usual manner, but which are constructed as hereinafter specified for the 30 reception of the couplers. The draw-heads *b* are bifurcated in form, as clearly shown in Fig. 2, and between the diverging portions is pivoted at *c* an elbow-shaped coupler *f*, upon the extremity of one arm *f'* of which is formed 35 a hook *f²*, while the remaining arm *f³* is widened at the end, as shown at *f'*, and in such widened portion is formed a slot *f⁵*, adapted to receive the hook *f²* of the coupler upon the opposite draw-head, said slotted arm forming 40 the equivalent of the ordinary link.

Pivotedly attached to a stud *g*, which is secured to the arm *f'*, is a small pulley *g'*, with which is connected a chain *i*, which is trained around pulleys *j j'*, attached to the car-body 45 above the draw-head and thence over pulleys *k k'*, arranged at the sides, respectively, and upon the ends of the cars. A frame or casing *l* is preferably provided to partially or wholly cover the chains and pulleys described.

50 Weights *m m'* are attached to the respective ends of the chain *i* for the purpose of normally holding the coupler, so that the hook

may be raised with the arm *f* in a vertical position, as shown at the left in Figs. 1 and 2, the weights being made sufficiently heavy to 55 counterbalance the arm *f'* and not to raise it when the latter is lowered to a horizontal position, as shown at the right in Figs. 1 and 2. The chain *i* is sufficiently long to permit the weights *m m'* to hang down below the pulleys 60 from which they are suspended, and upon grasping one weight and pulling downwardly the weight upon the opposite side is raised until it can ascend no farther, when a further pull serves to raise the arm *f'* and lift the 65 hook *f²* from engagement with the slot *f⁵* in the companion coupler. The position of the weight when the arm *f'* is raised is shown at the left in Fig. 1. Upon raising the weight *m*, and thus loosening the chain, the arm *f'* is 70 permitted to fall.

Should the operator desire to lower the arm *f'* while he is upon the side of the car upon which the weight is raised, he first draws the chain through the pulleys to its fullest extent 75 and then raises the weight of which he has hold, which permits the arm *f'* to fall into the slot *f⁵* of the arm *f³*, which is normally in a horizontal position, and as the weight upon but one car is raised at a time it is obvious 80 that the couplers cannot fail to engage with each other.

If desirable at any time to employ an ordinary link and coupling-pin, it may be done by forming lateral projections *b' b'*, which are 85 provided with bores *b²*, Fig. 2, for the reception of a coupling-pin *b³*, Fig. 3. Thus it will be seen that my improved coupler may be employed upon any car and not only used upon other cars to which it is attached, but in connection with cars having the ordinary coupler. 90

Among the advantages of my improved coupler is its simplicity, durability, and cheapness, coupled with the fact that the operator is not obliged to pass between the cars in 95 using it.

Having thus described my invention, I claim—

1. A car-coupler consisting of two elbows pivotally secured in opposite draw-heads, each 100 of said elbows having a hook upon the extremity of one arm and a corresponding slot at or near the extremity of the other, and means for tilting said elbows upon their pivots, whereby

the hook upon the arm in one draw-head may enter the slot in the arm pivoted within the other, substantially as shown and described.

2. The combination, with the draw-heads 5 $b b$, of the hooked and slotted elbow-couplers f , pivoted, respectively, within the draw-heads, and means for oscillating said elbows upon their pivots, substantially as shown and described.

10 3. The combination of the bifurcated draw-heads $b b$, elbows f , hooked and slotted, as described, and pivoted within said draw-heads, chains trained over pulleys and loosely attached to the arms $f' f'$, and counterpoise-15 weights $m m'$, substantially as shown and described.

4. In a car-coupler, the combination, with

the draw-heads, of the pivoted elbow-couplers f , hooked and slotted, as specified, chains i , trained loosely over pulleys attached to the 20 car-body and arms f' , respectively, said chains being of a sufficient length to permit the arm f' to descend to a horizontal position, and counterpoise-weights upon the respective ends of said chains, substantially as shown and de-25 scribed.

In testimony whereof I have signed this specification, in the presence of two subscribing witnesses, this 2d day of July, 1890.

ALEXANDER C. MARTIN.
